UNITED STATES PATENT OFFICE.

CHARLES CLARK, ROBERT CHARLES CLARK, AND ARTHUR BERNARD CLARK, OF RETFORD, ENGLAND.

APPARATUS FOR DYEING ARTICLES OF CLOTHING, FABRIC, AND THE LIKE.

Application filed July 12, 1926, Serial No. 122,005, and in Great Britain December 8, 1925.

This invention relates to improvements in apparatus for dyeing articles of clothing, fabrics and the like.

According to the invention the apparatus 5 comprises a vat constructed with one side of curved formation, the curvature extending upwards and outwards from a horizontal portion of the bottom and with the other side extending vertically upwards for some 10 distance and then curving inwards towards the other side, a space being left at the top between the two sides through which the dye liquor and the garments or fabrics to be dyed can be inserted.

15 This construction of vat enables the dye liquor to circulate with the articles or fabric, without the use of mechanical stirring devices when compressed air with or without steam is forced into the vat near the bottom where the horizontal portion of the latter meets the vertical portion of the side.

20 Another feature of the invention consists in forcing compressed air for the circulation into the vat in front of the supply of steam for heating purposes, the compressed air keeping the articles or fabrics being dyed from coming into contact with the live steam or the steam pipe.

25 The invention will be described with reference to the accompanying drawings.

Fig. 1 is a transverse section of the vat.

Fig. 2 is a longitudinal section of same.

Fig. 3 is a plan of same.

30 Fig. 4 is a detail section of drying and testing device.

The vat A is constructed with one side a of curved formation, the curvature extending upwards and outwards from the horizontal bottom a¹ and then inwards again 40 towards the top as shown in Fig. 1. The other side a² is perpendicular for part of its height and then curves inwards towards the side a. An aperture or space a³ is left between the sides a and a² through which 45 the dye liquor and the articles to be dyed can be introduced into the vat.

The ends a⁴ of the vat are arranged vertically and the whole vat is held together by rods a⁵ passing through the ends but arranged outside the sides a and a². A drain pipe with cock (not shown in the drawings) is arranged at the bottom of the vat for draining off the liquor.

50 A board or cover A¹ is arranged over the top of the side a² to partially enclose the

latter and form a ledge or table on which the articles to be dyed can be placed before being inserted into the vat.

Two perforated pipes B and C are arranged near the bottom of the vat in the 60 angle between the horizontal bottom a¹ and the vertical portion of the side a². The pipe B nearer to the side a² is connected to the supply of steam for heating the dye liquor and the pipe C is connected to a fan 65 or blower for supplying air under pressure for circulating the dye liquor. Bars or battens b¹, b² and b³ are provided respectively between the side a² and the pipe B between the pipe B and the pipe C and between the pipe C and the bottom a¹ to prevent the articles being dyed from passing under the pipes.

70 This arrangement of separate pipes for the compressed air and for the steam with the pipe C for the compressed air in front of the pipe B for the steam prevents the articles being dyed from coming into contact with the live steam or the steam pipe.

75 In the steam supply pipe B¹ there is arranged a device D connected to the compressed air supply pipe C¹ through the pipe d fitted with the valve d¹. The device D is arranged adjacent to the top of the vat A and is employed for rapidly drying a 80 small portion of the article or fabric being dyed for matching or testing purposes. The device D comprises a number of tubes d² connected at each end to headers D¹, D² through which tubes compressed air passes 85 when the valve d¹ is turned on, the air being heated by the passage of the steam through the device and around the tubes.

90 Thus when it is desired to dry a small portion of the article or fabric for matching, this portion is held in front of the outlet d³ from the device D and the supply of air turned on, the portion in front of the orifice d³ being then rapidly dried.

95 What we claim as our invention and desire to protect by Letters Patent is:—

1. A dye vat comprising the combination with a base, sides, and ends, of a perforated pipe for supplying steam to the contents of the vat and a second perforated pipe for supplying compressed air arranged in front of the first perforated pipe to keep the articles being dyed from coming into contact with the steam pipe.

100 2. A dye vat comprising in combination,

a base, a side of curved formation, the curvature extending upwards and outwards from the base, a second side extending vertically upwards from the base and then curving inwards towards the other side, two vertical ends, a cover extending over the second side, a perforated pipe for supplying steam to the contents of the vat and a second

perforated pipe for supplying compressed air arranged in front of the first perforated pipe.

In testimony whereof we have hereunto set our hands.

CHARLES CLARK.

ROBERT CHARLES CLARK

ARTHUR BERNARD CLARK.
